UNITED STATES PATENT OFFICE.

HERMANN KELLER, OF HILTON, NEW JERSEY, ASSIGNOR TO FORSTNER CHAIN CORPORATION, OF IRVINGTON, NEW JERSEY, A CORPORATION OF NEW JERSEY.

METHOD OF FORMING FLEXIBLE TUBING.

Application filed April 9, 1927. Serial No. 182,325.

This invention relates to a method of forming a flexible tube from a plurality of helically wound strips of material and has for its object to provide a method by which the coils are spaced apart by an intermediate filling strip and this strip removed after the coils are formed.

A further object of the invention is the use of a filling strip to support the coils against pressure for operations on the surface of the outer coils to enhance the appearance thereof and then removing the filling strip.

With these and other objects in view, the invention consists of certain novel features of construction, as will be more fully described and particularly pointed out in the appended claims.

In the accompanying drawings:

Figure 1 is a perspective view of a bracelet formed by my improved method.

Figure 2 is a fragmental section showing the finished tube.

Figure 3 is a fragmental section showing the intermediate filling strip as interposed between the outer and inner coils before the same has been removed.

Figure 4 is a side elevation showing the plurality of strips placed side by side upon an arbor to form a tube of different appearance.

Figure 5 is a sectional view illustrating the tube as being drawn through a die to cause the outer surface to have a uniform appearance.

Figure 6 is a sectional end view of the tubing flattened.

Figure 7 is a sectional fragmental view of the coils after being pressed on their outer surfaces for ornamentation.

Figure 8 is a view similar to Figure 7 with the intermediate filling strip removed.

Figure 9 is a perspective view of the filling strip.

Figure 10 is a perspective fragmental view of the filling strip located in one of the channel strips.

It is found in practice in the making of helical tubing for ornamental purposes such as bracelets, chokers and the like desirable to make the same extremely flexible and at the same time ornament the outer surface of the outer coils by pressing recesses therein and in order to accomplish these results, I have laid a strip of aluminum or some material

different from the inner and outer coils in the channels of the strips of either the inner or outer coils to support the coils during the operations thereon and then chemically remove this filling strip by dissolving it to leave a greater space between the coils for increasing their flexibility; and the following is a detailed description of the present method by which these advantageous results may be accomplished:

With reference to the drawings, 10 designates the outer strip and 11 the inner strip of material, each channel-shaped in cross section with the flanges 12 of two adjacent outer strips lying within the channel between the flanges 13 of one of the inner coils and with a filling strip 14 disposed in the channel of the inner strip to support the outer strip. The construction illustrated in Figures 2 and 3 consists of a single inner strip and a single outer strip wound into helical formation one about the other over an arbor such as 15 with the flanges in the inner strip extending outwardly and the flanges on the outer strip extending inwardly and straddling the point between adjacent coils of the inner strip, by a process well known, however, I have added in the channel of one of these coils a filling strip 14 illustrated in Figure 3 in the inner coil, 85 which provides a support for the outer coil so that its outer surface which may be roughened or uneven, as illustrated at 16 in Figure 5 may be smoothed by drawing the same through a suitable die 17 and at the same time this drawing operation may cause a change in the shape of the tube from round to elliptical as illustrated at 18 in Figure 6, it being necessary that the outer coils should be supported by the filling strip 14 in order that the change in shape, illustrated at 18, may be formed.

In some instances, it is desirable to ornament the outer strip 10 which I may do only when the filling strip is used by pressing recesses 19 in its outer surface as illustrated in Figure 7 which may of themselves be of an ornamental configuration to enhance the appearance of the bracelet or which may receive further ornamentation such as gems or the like. After the drawing operation and ornamental formations are completed the filling strip 14 having served its usefulness is then removed from between the inner and outer coils by chemically dis-

solving it. The filling strip is of a material different from the inner and outer coils, aluminum being found as one material which will serve this purpose. The removal of 5 this strip leaves a space 20 between the flanges of the outer strips and inner strips 11 to allow greater freedom of the coils and flexibility of the tube when in use.

In some cases a plurality of strips for the 10 inner and outer coils may be wound simultaneously about the arbor 15 as illustrated in Figure 4. A pair of strips 21 and 22 each having a filling 14 of different material, are wound as a pair simultaneously to form the 15 inner coils and a pair of strips 23 and 24 having different outer surfaces are wound simultaneously side by side about the inner coil to form the outer coil of the tube each 20 of the strips being channel shaped with their inwardly extending flanges on the outer coil interlocked with the outwardly extending flanges on the inner coil to limit the closing movement of the coils with relation to each other.

25 It will be seen from the foregoing process that I have provided a method by which certain operations to increase the ornamental appearance of the tube may be performed after which the filling strip necessary in 30 order that such operations may be performed is removed to increase the flexibility of the bracelet which is also an improved and desirable result in the finished product.

Having thus described one illustrative embodiment of my invention and the best mode known to me for carrying out my method, I desire it to be understood that although specific terms are employed, they are used in a generic and descriptive sense and not for 40 the purpose of limitation, the scope of the invention being defined and limited only by the terms of the appended claims.

I claim:

1. A method of forming an ornamental tubing, which consists in winding a plurality of channel-shaped strips of metal into helical coils one upon the other with the inwardly-extending side flanges of each outer coil extending into the channels between 50 outwardly extending side flanges of adjacent inner coils and at the same time winding into helical form a filling strip of a different material than that of the inner and outer coils and positioned in the channels of one 55 of them, and then removing the filling strip after the coils are formed.

2. A method of forming an ornamental tubing, which consists in winding a plurality of channel-shaped strips of metal into helical coils one upon the other with the inwardly-extending side flanges of each outer coil extending into the channels between outwardly extending side flanges of adjacent inner coils, and at the same time winding 60 into helical form a separate strip of a mate-

rial different than the material of either inner or outer coils and positioned in the channels of the inner coil when wound, drawing the tube when wound through a die to smooth the outer surface and then removing 70 the filling strip.

3. A method of forming an ornamental tubing, which consists in winding a plurality of channel-shaped strips of metal into helical coils one upon the other with the inwardly-extending side flanges of each outer coil extending into the channels between outwardly-extending side flanges of adjacent inner coils, and at the same time winding into helical form a separate strip 80 of a material different than the material of either the inner or outer coils and positioned in the channels of the inner coil when wound, drawing the tube when wound through a die to smooth the outer surface, pressing the outer surface of the outer coils for ornamentation and then removing the filling strip. 85

4. A method of forming an ornamental tubing, which consists in winding a plurality of channel-shaped strips of metal into 90 helical coils one upon the other with the inwardly-extending side flanges of each outer coil extending into the channels between outwardly extending side flanges of adjacent inner coils and at the same time winding into 95 helical form, a separate strip of a material different than the material of either inner or outer coils the strip being positioned in the channels of the inner coil when wound, pressing the outer surface of the outer coils 100 for ornamentation and then removing the filling strip.

5. A method of forming an ornamental tubing, which consists in winding a plurality of channel-shaped strips of metal into helical coils one upon the other with the inwardly-extending side flanges of each outer coil extending into the channels between outwardly extending side flanges of adjacent inner coils and at the same time winding 110 into helical form a filling strip of a different material than that of the inner and outer coils and positioned in the channels of one of them, and then dissolving the filling strip after the coils are formed. 115

6. A method of forming an ornamental tubing, which consists in winding a plurality of channel-shaped strips of metal into helical coils one upon the other with the inwardly-extending side flanges of each outer coil extending into the channels between outwardly extending side flanges of adjacent inner coils, and at the same time winding 120 into helical form a separate strip of a material different than the material of either the inner or outer coils the strip being positioned in the channels of the inner coil when wound, drawing the tube when wound through a die to smooth the outer surface, pressing the outer surface of the outer coils for ornamentation 125 130

tation and then dissolving the filling strip after the coils are formed.

7. A method of forming an ornamental tubing, which consists in winding a plurality of channel-shaped strips of metal into helical coils one upon the other with the inwardly-extending side flanges of each outer coil extending into the channels between outwardly extending side flanges of adjacent inner coils, and at the same time winding

into helical form a separate strip of a material different than the material of either inner or outer coils the strip being positioned in the channels of the inner coil when wound, drawing the tube when wound through a die ¹⁵ to smooth the outer surface and change the shape of the tube from cylindrical, and then removing the filling strip.

In testimony whereof I affix my signature.
HERMANN KELLER.
